Primary Examiner—A. Hugo Word*Assistant Examiner*—Celia Murphy*Attorney, Agent, or Firm*—Richard C. Litman**[57]****CLAIM**

The ornamental design for pocketed underwear, as shown and described.

DESCRIPTION

FIG. 1 is a front perspective view of my new design for pocketed underwear;

FIG. 2 is a front elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a rear elevational view thereof;

FIG. 8 is a front perspective view of an alternate embodiment of the design shown in FIG. 1;

FIG. 9 is a front elevational view of the embodiment of FIG. 8;

FIG. 10 is a left side elevational view of FIG. 8;

FIG. 11 is a right side elevational view of FIG. 8;

FIG. 12 is a top plan view of the embodiment of FIG. 8; and,

FIG. 13 is a bottom plan view of the embodiment of FIG. 8.

The rear elevational view of the second embodiment of FIGS. 8 through 13 is identical to the rear elevational view of the first embodiment shown in FIG. 7. The pocket flap is shown in an open position in each of the figures where the pocket is disclosed.
